FOLDING MACHINE

Elmer D. Coston, St. Louis, Mo., assignor to Manufacturers Supplies Company, St. Louis, Mo., a corporation of Missouri

Application March 21, 1940, Serial No. 325,127

13 Claims. (Cl. 12—55)

This invention relates, generally, to folding machines, and particularly to machines for folding leather parts, such as shoe upper pieces.

In the manufacture of shoes and other leather articles, it is customary, in order to provide a neat joint between separate parts, to skive the edges of the pieces of leather and fold the same so that the grain side of the leather extends completely about the margin. While a variety of machines have heretofore been provided for accomplishing such a folding operation, such machines have generally been of such complicated character that substantial rebuilding was required in order to adapt the machine to handle differently shaped pieces of leather; and in other cases such machines were of a character such that a high degree of skill of the operative was required to accomplish the desired result, and even in such cases non-uniformity between the various pieces of work resulted.

The object of the present invention, generally stated, is to provide a folding machine of a character which may be readily adapted to operate upon differently shaped pieces.

A further object of the present invention is to provide a folding machine of the character described wherein the fold is produced by a combined wiping and pressing action of the active members.

Another object of the present invention is to provide a folding machine of the character described, so constructed and arranged that the active gauging and folding parts may be removed and replaced by simple manipulations, without requiring the services of a skilled mechanic.

Other objects will become apparent to those skilled in the art when the following description is read in connection with the accompanying drawings, in which:

Figure 1 is a plan view of a folding machine, constructed in accordance with the present invention.

Figure 2 is a sectional view taken along line 2—2 of Figure 1.

Figure 3 is a sectional view taken along line 3—3 of Figure 1.

Figure 4 is a sectional view taken along line 4—4 of Figure 1.

Figure 5 is a plan view of the machine shown in Figure 1, with the active gauging and folding parts removed.

Figure 6 is a sectional view taken along line 6—6 of Figure 5.

Figure 7 is a sectional view, somewhat diagrammatic in form, and illustrating the gauging

and forming parts in exaggerated relation, at the beginning of the folding operation.

Figure 8 is a view corresponding to Figure 7, but showing the parts at a subsequent phase of the folding operation.

Figure 9 is a view similar to Figures 7 and 8, but showing the parts at a farther advanced stage of the folding operation.

Figure 10 is a view similar to Figures 7, 8, and 9, but showing the parts in the final stage of the folding operation.

Figure 11 is a plan view of a piece of leather, shaped in conformity with the gauging and forming elements of the device shown in Figure 1, in condition ready to be operated upon thereby.

In accordance with the present invention, generally stated, a folding machine is constructed and arranged so as to be operated in any suitable press, such for example as one in which a

20 plunger or other suitable head is operated downwardly toward a bed. The present invention contemplates that the folding machine for operation in conjunction with such a press be provided, on its upper surface, with suitable gauging, forming, and folding elements of a character such that they may be readily removed from the adjunct mechanism, and replaced by others, thereby to adapt the machine for easy conversion to handle differently shaped pieces of leather, or other material, to be folded.

The present invention further contemplates that the parts of the folding machine which contact directly with the material to be folded be arranged so as to be moved laterally with relation to the material being operated upon, so as to wipe the fold being formed with slight pressure, and thereafter, when the wiping movement has been completed, to subject the folded material to the direct pressure of the press in a direction normal to the surface of the material being folded.

Referring now to the drawings for an illustrative embodiment of the present invention, the folding machine comprises a base 1, which may be provided with suitable guides, such for example as a channel 2, in the bottom surface thereof for cooperation with suitable rails arranged upon the bed of a pressure machine in which the device is intended to be used. Extending upwardly from base 1 is a plurality of posts 3, supporting at their upper ends an auxiliary base 4. Obviously, the guide rails 2 may be mounted directly upon the auxiliary base 4 when it is desired to reduce the overall height of the supporting apparatus.

The auxiliary base 4 provides a support upon which is mounted a plurality of yieldable supporting members 5, one adjacent each corner of the mechanism. Mounted upon the upper end of posts 5 is a work support 6.

As shown clearly in Figure 4, the yieldable members 5 are, in the embodiment illustrated, composed of telescoping members 7 and 8, about which is provided a coil spring 9, arranged so as to maintain the telescoping members 7 and 8 in 10 extended position.

Also arranged upon auxiliary base 4 is a plurality of studs 10, arranged so as to limit the downward movement of work support 6 relative to auxiliary base 4, it being understood that when 15 the work support 6 is moved downwardly until the lower surface thereof contacts the upper ends of studs 10, further downward movement of work support 6 relative to auxiliary base 4 is precluded.

Arranged in work support 6 is a plurality of members 11, arranged to receive the impact of the head of the press in which the mechanism is operated. The members 11 are mounted upon coil springs 12, carried in cups 13, which are secured beneath work support 6. The springs 12 are of a character such as to maintain members 11 in their uppermost position, as shown in Figure 4, until springs 9 have yielded to such an extent that work support 6 is seated upon the upper ends of studs 10. Thereafter, further 30 movement of the pressure device forces members 11 downwardly within cups 13, against the resistance of springs 12.

Work support 6 is provided with a pair of openings 14, and a second pair of openings 15, as 35 clearly illustrated in Figure 5. The openings 14 and 15 are respectively provided with internal shoulders 16 and 17.

Mounted in openings 14 so as to slide upon shoulders 16 is a pair of blocks 18, connected together beneath work support 6 by a transverse cam member 19; and each of blocks 18 is provided with an upwardly-extending stud 20, arranged to receive an element of the gauging and forming mechanism. Interposed between camming member 19 and the lower surface of work support 6 is a plate 21, extending beyond the margins of openings 14, so as to provide a guiding and holding means operating against the lower surface of work support 6.

Similarly, a pair of blocks 22 are mounted in openings 15, and connected together beneath work support 6 by a camming member 23. Guiding and holding plate 24, corresponding in form and function to plate 21, is likewise provided for 55 the parts mounted in opening 15.

It will be observed that openings 14 and 15 are respectively longer than their corresponding blocks 18 and 22, so that lateral movement of the blocks with their adjunct mechanism in the openings is thereby permitted. On the lower surface of work supporting member 6, a spring 25 is provided for biasing the sliding mechanism, mounted for movement in openings 14, toward the right; and similarly, a spring 26 is provided for biasing the sliding mechanism, provided in openings 15, toward the right.

Mounted upon auxiliary base 4 is an abutment block 27, arranged for cooperating with camming member 19, so that upon downward movement of 70 work support 6 and its adjunct parts, camming member 19 engages with abutment 27, and the former, together with blocks 20, is moved toward the left.

A similar abutment block 28 is provided for 75

cooperation with camming member 23, and arranged to move blocks 22 with their associated parts toward the left, upon downward movement of the work support. The camming surfaces of members 19 and 23 are coordinated with blocks 27 and 28, so that while lateral movement of member 19 with its associated parts is initiated before lateral movement of member 23 with its associated parts begins, the lateral movement of member 23 is at a greater rate than the lateral movement of member 19, and consequently, with the parts arranged as shown in the drawings, lateral movement of member 23 is completed before lateral movement of member 19 is completed.

Mounted upon work support 6, so as to be movable in association with camming member 19, is a wiping element 29 having an edge conforming generally to the edge configuration of the piece of material to be folded. At the edge 30, the lower surface of wiping element 29 is beveled as shown clearly in Figures 4, 5, and 7 to 10 inclusive. Mounted upon wiping element 29 is a gauge element 31, having an edge 32 conforming in size and shape to the edge configuration of the piece of material to be folded. Edge 32 is spaced slightly from edge 30 of wiping element 29, so that edge 32 provides an abutment against which the edge of a piece of material to be operated upon may be placed, in gauging the work.

Wiping element 29 is provided with a pair of openings 33, arranged to receive studs 20 in blocks 18, so that upon lateral movement of blocks 18 wiping element 29 moves laterally to the same extent. Wiping element 29 is, however, not held against upward movement relative to blocks 18, except by its own weight; and consequently the wiping element may be readily removed by lifting from studs 20, and replaced at will.

A forming member 34, having an edge configuration substantially conforming to the configuration of edge 30 of wiping element 29, is mounted upon blocks 22 for lateral movement therewith. In the embodiment shown in the drawings, forming member 34 is of bail formation, with its active edge 35 drawn relatively thin, but not sharp enough to cut the material to be acted upon. Forming member 34 is connected through hinges 36 to the respective blocks 22. In the embodiment shown in the drawings, one half of each hinge 36 is mounted upon blocks 22, while the companion half-hinge is mounted upon forming member 34; and hinge pins 37 are provided with an angularly extending part 38, so that they may be readily gripped and removed.

A hold down member 39 is hingedly mounted at 40 upon the upper surface of work support 6, so that hold down member 39 remains stationary when the adjacent parts are moved laterally relative to work support 6. In the embodiment shown, hold down member 39 is formed of a body piece and an edge part 40, the edge part 40 being mounted upon the lower surface of body piece 39 and being tapered at 41, as clearly shown in Figures 7, 8, and 9, so as to provide a cam surface arranged to lift forming member 34 slightly away from work support 6, as the forming member is moved laterally to the left.

In order to concomitantly lift hold down member 39 and forming member 34, so as to permit the placement of a piece of work in the apparatus, a handle 42 is provided on hold down member 39 and arranged to extend laterally beneath forming member 34 sufficiently to permit the same to be grasped and lifted by an operative.

Extending beneath forming member 34, it is apparent that upward movement of handle 42 raises not only hold down member 39, but forming member 34, which is thereabove.

In order to provide for convenient and expeditious removal of hold down member 39, hinges 40 are provided with a hinge part 43 having a laterally extending part 44 which may be conveniently grasped and removed when it is desired to substitute one hold down plate for another.

Since in the substitution of parts, (wiping element, forming member, and hold down plate), in order to adapt the machine to differently shaped pieces of work, it is frequently desirable to vary the space between edge 30 of wiping element 29 and edge 35 of forming element 34, means is provided for adjusting at spaced relation therebetween when the parts are at rest. Such an adjusting means may consist of a rod 45 secured at one end to camming member 23, and extending through a boss 46 on the lower surface of work support 6. Rod 45 is provided, at its outer end, with threads to receive suitable adjusting nuts 47; and accordingly, when it is desired that the space between edge 35 of forming element 34 and edge 30 of wiping element 29 be increased beyond that shown in the drawings, (when the parts are at rest), nuts 47 may be run up on rod 45, thereby drawing camming member 23, (with blocks 22 and forming member 34), leftwardly against the tension of spring 26.

Under some circumstances it is desirable to lock the slide carrying forming member 34 temporarily in position away from the edge of wiping element 29, and in order to accomplish this result, a latch 48 arranged to engage over the edge of work support 6 is provided, as shown in Figures 1 and 3.

In the operation of the device, a piece of leather such as 49, having a skived margin 50 to be folded, after having a suitable adhesive applied, is placed upon work support 6 with the skived margin 50 abutted against edge 32 of gauge 31 upon wiping element 29. Hold down member 39 is then closed upon the work until edge part 140 rests upon the upper surface of leather 49, as clearly shown in Figure 7. Thereupon, forming member 34 is brought down into position until edge 35 thereof contacts with the leather piece 49, and breaks the same upwardly into the position shown in Figure 8. With the parts in this position, the head of the pressure machine illustrated diagrammatically in Figures 7 to 10 inclusive as 51 may be brought down upon the folding mechanism, the impact of head 51 being received by members 11; and since springs 9 are arranged to yield before yielding of springs 12 takes place, the work support and its adjunct parts are moved downwardly relative to auxiliary base 4, telescoping members 7 and 8. During this downward movement, abutment 27 engages the inclined surface of camming member 23, and moves the same laterally, thereby moving wiping element 29 to the left over the edge 35 of forming member 34, as clearly shown in Figure 9. At this point in the operation, however, springs 12 have not yielded under the force of the pressure member; and consequently little, if any, vertical pressure is being applied by head 51 to wiping element 29.

Further downward movement of work support 6 with its adjunct parts effects an engagement between abutment 28 and the inclined surface of camming member 23, with the result that camming member 23 with its adjunct parts, including block 22 and forming element 34, are moved

to the left, pulling the edge 35 of forming element 34 out of the fold beneath edge 30 of wiping element 29. As the forming element 34 is being moved leftwardly, wiping element 29 continues its leftward movement, wiping the fold from right to left, as seen in Figures 9 and 10. When finally the lateral movement of wiping element 29 has been completed, work support 6 comes to rest upon studs 10, and springs 12 begin to yield under the pressure of head 51, with the result that the head comes to rest upon gauge member 31, and forces wiping element 29 downwardly upon the fold in material 49.

Upon release of head 51, the series of movements just described are reversed until the various parts have resumed their positions illustrated in Figure 1; whereupon the operator may lift handle 42, concurrently raising forming member 34 and hold down member 39, so as to permit removal of the folded material from the machine, and insertion of another piece to be operated upon.

When it is desired to convert the folding mechanism so as to adapt it to handle differently shaped pieces of leather or other material from that illustrated in Figure 11, it is apparent that wiping element 29 may be readily removed by simply lifting the same from studs 20. Forming member 34 may be readily removed by simply withdrawing pins 37 from hinges 36; and hold down member 39 may be readily removed by withdrawing hinge pin 43 from hinge 40. Other corresponding parts, differently shaped in accordance with the work to be operated upon, may then be substituted by a reversal of the operations. Such an arrangement provides for ready removal and replacement of the only parts of the device which need be changed when converting the machine from one piece of work to another, and consequently versatility of operation is accomplished with a minimum of expense.

While it is apparent that the foregoing description and the accompanying drawings constitutes a detailed disclosure of one embodiment of the folding machine according to the present invention, it is evident that many variations in the mechanical arrangements will present themselves to those skilled in the art, and consequently it is to be understood that it is contemplated that under many circumstances and conditions it will be desirable to replace specific elements of the device herein disclosed with their mechanical equivalents. It is further contemplated that other operations may be carried out concurrently with the folding operation herein described in detail. For example, by the provision of suitable inking or cutting dies for operation through apertures in work support 6, a cut out or a pattern marking or both may be applied to the piece of leather concurrently with the folding.

It is therefore to be distinctly understood that such modifications, adaptations, and rearrangement of parts as do not depart from the spirit of this invention, are, although not specifically claimed herein, contemplated by and within the scope of the appended claims.

Having thus described the invention, what is claimed is:

1. A machine for folding parts of material such as leather, comprising, a work support for holding a piece of material to be folded, a wiper having an edge gauge arranged to abut the unfolded edge of the piece to be folded, a forming

member having a forming edge arranged to depress the material to be folded below the surface of said wiper, a hold down plate, and means for moving said wiper and said former laterally relative to each other and to the hold down plate, said wiper arranged to bear unrestrainedly against the work support.

2. A machine for folding parts of material such as leather comprising, a forming member, a wiping member, means for moving said members laterally relative to the material being folded so that the wiping member is juxtaposed with the fold and continuously bearing downwardly thereon during such movement, and means for applying vertical pressure to the wiping member when in said juxtaposed position.

3. The combination with a press having a vertically movable head, of a folding machine having a forming member, a wiping member, and means operable in response to pressure from the head of said press for moving said forming and wiping members laterally relative to the material being folded, said wiping member being in position to receive the force of said press, and means for protecting said wiping member from receiving the full force of said press until the wiping member is juxtaposed with the fold.

4. The combination with a press having a vertically movable head of a folding machine having a work support, a wiping member mounted on said work support for lateral movement, a forming member mounted on said work support for lateral movement, cam means for moving said forming member and said wiping member laterally at different rates in response to downward movement of the work support under pressure of the press head, and yieldable means arranged to maintain said press head out of engagement with the wiping member until lateral movement thereof has taken place.

5. A device of the kind described comprising a work support, a slidable member guided for movement in said work support, and a wiping member riding upon the surface of said work support and coupled to said slidable member.

6. A device of the kind described comprising a work support, slidable members guided for movement in said work support, and a wiping member riding upon the surface of said work support and coupled to said slidable members for lateral movement therewith but unrestrained against vertical movement relative to said work support and slidable members.

7. A device of the kind described comprising a work support, slidable members guided for movement in said work support, and a forming member hinged to said slidable members for lateral movement therewith.

8. A device of the kind described comprising a work support, a pair of slidable members guided for movement in said work support, each of said slidable members having an upstanding stud, a wiping member arranged to ride upon the surface of said work support and having a pair of

holes therein spaced according to the spacing of the studs on said slidable members and arranged to receive the same, said wiping member being free of direct connection to said work support.

5 9. A device of the kind described comprising a work support, two pairs of slides mounted in said work support, each of said slides having coupling parts extending above the surface of said work support, a wiping member connected with the coupling parts on one pair of said slides, said wiping member having a gauge device thereon, a forming member connected with the coupling parts on the other pair of slides, the edge of said forming member corresponding in outline to said gauge device, and a hold down member connected to said work support.

10 10. A device of the kind described comprising a work support, two pairs of slides mounted in said work support, each of said slides having coupling parts extending above the surface of said work support, a wiping member connected with the coupling parts on one pair of said slides, said wiping member having a gauge device thereon, a forming member connected with the coupling parts on the other pair of slides, the edge of said forming member corresponding in outline to said gauge device, a hold down member connected to said work support, and means operable upon depression of said work support to move said wiping member and said forming member laterally relative to said hold down member.

20 11. A device of the kind described, comprising, a work support for receiving a piece to be folded, means for breaking the piece at the fold to be formed, a wiper, and means for moving the wiper against and over the piece in continuous bearing contact therewith from the bight of the fold inwardly.

30 12. A device of the kind described, comprising, a work support for receiving a piece to be folded, means for breaking the piece at the fold to be formed, a wiper normally sustained at the plane of the work support but being movable vertically relative thereto, and means for moving the wiper against and over the piece in continuous bearing contact therewith from the bight of the fold inwardly, the forward edge of said wiper having an undercut bevel to guide it over the bight of the fold.

40 13. A machine for folding parts of material such as leather, comprising, a work support for receiving the work piece, a wiper having a ledge elevated above the support for sustaining the margin of the work piece above the work support, a forming member provided with an edge movable into horizontally spaced relation proximate said ledge, the edge of said forming member being compressible below the plane of said ledge to break the fold in the work piece, and means for moving said wiper toward the edge of said forming member and onto and over the fold in the work piece in continuous bearing contact therewith.

ELMER D. COSTON.
